FUEL-AIR RATIO REGULATOR FOR INTERNAL-COMBUSTION ENGINES

Joseph Albon Bascle, New Orleans, La.

Application August 30, 1949, Serial No. 113,142

14 Claims. (Cl. 123—119)

1

The present invention relates to improvements in fuel-air ratio regulator for internal combustion engines and has for its object to provide an improved regulator which in one use and application of the device will compensate for the relatively wide variations in output of the conventional fuel pumps as found today on motor vehicles, tractors and marine engines; and which will also supplement the action of pressure carburetors in a manner to assure better engine performance and higher engine power output.

In the present-day operation of motor vehicles, tractors, marine engines and the like, fuel is delivered to the carburetor by conventional diaphragm type fuel pumps, the construction of which is such that the output or fuel delivery of these pumps varies so widely that the volume and pressure of the fuel delivered at any one time to the carburetor jets is in such a variable quantity that it is difficult to make carburetor adjustments, and it is also difficult to control the fuel air ratio so much so that engine performance throughout varying speeds and loads suffers; and it is one object of the present invention to correct this situation by introducing as a supplementary control unit the improved regulator of this invention, which will receive the fuel in varying volume from the conventional fuel pump but thereafter will supply such fuel in a controlled and assured volume at all times to the carburetor to the end of bettering engine performance and arriving at better estimated fuel air ratios which may be controlled at all speeds and loads.

In the case of pressure carburetors and in view of the absence of the balancing effect of the float and pin assembly, fuel is delivered to the carburetor jets in widely variable volume and pressure which is also incident to variable pump supply; and it is the object of the present invention to provide an improved regulator unit interposed between the carburetor and the pump for supplying the fuel to the carburetor jets in regulated and controlled volume and pressure values in which particularly both the volume and pressure of the fuel will assist or coordinate with the carburetor action to provide a more suitable air fuel ratio to meet the operating conditions of the engine.

The invention also has for its object to take into account and to compensate for varieties of fuels in which the fuel values and ratings are at widely different expansion values.

One of the purposes of the invention is to isolate the improved regulator from the carburetor

2

and to create an independent unit as a regulator to admit of its being moved to various locations, for instance in the case of low-grade fuels, the device may be placed in a position relative to the exhaust manifold which will thereby acquire a certain amount of heat from the exhaust manifold to preheat the low-grade fuel prior to its introduction to the carburetor; or, in which the device admits of being placed in a colder location, for instance as shown in Figure 1, when used in connection with highly volatile fuels.

It is the further purpose of the invention to provide an improved regulator and control therefore which when used in connection with pressure carburetors may be substituted for the conventional choke valve and its control; and when used on airplanes may take the place of the usual altitude control device.

It is the further purpose of the present invention to cooperate in a novel manner with the customary A-C. or similar diaphragm type fuel pumps in which the diaphragm is drawn down by a cam shaft actuated lever, the diaphragm being spring loaded so that the pump may idle and vary its output where the requisition for fuel diminishes. With such a pump the pressure and volume factors are so variable as not to maintain at times an adequate supply of fuel at requisite pressure to the pressure carburetor; while at other times there is an over supply of fuel. It is therefore the purpose of the present invention to control these variances and thereby further condition the fuel supply for use by the carburetor jets.

With the foregoing and other objects in view, the invention will be more fully described hereinafter, and will be more particularly pointed out in the claims appended hereto.

In the drawings, wherein the symbols refer to like or corresponding parts throughout the several views,

Figure 1 is a diagram illustrating one form of hook-up of the improved regulator to the exhaust manifold, conventional fuel pump and a pressure carburetor to an internal combustion engine.

Figure 2 is a perspective view of the improved regulator shown apart from the engine hook-up and with the actuating lever in an initial or origin position.

Figure 3 is a fragmentary perspective view, with parts shown in section, taken on an enlarged scale, of the regulating unit.

Figures 4, 5 and 6 are diagrammatic views showing in sequence the several phases of operation of the unit.

Figure 7 is a vertical section taken transversely through the casing, diaphragm and tapered pin valve.

Figure 8 is an exploded perspective view of the casing members, diaphragm and gaskets.

Figure 9 is an exploded perspective view of the diaphragm valve and its assembly, and

Figure 10 is a vertical section taken on an enlarged scale on the line 10-10 of Figure 2.

Referring more particularly to the drawings, 15 and 16 indicate identical half sections or members of a casing containing a diaphragm 17 which divides the interior of the casing into an exhaust pressure chamber 18 and a fuel pressure chamber 19.

The marginal portion of the diaphragm 17 together with appropriate gaskets 81 and 82 is clamped between the annular margin portions of the casing members 15 and 16 and such casing members are tightly secured upon the margin of the diaphragm by means of bolts or other fastenings 20.

The pressure chamber 18 is placed in direct communication with the exhaust manifold 21 of the internal combustion engine, shown in Figure 1, through a pipe or conduit 22. As installed (Fig. 1) the pipe 22 connects with the regulator unit at the lower portion thereof through a hollow boss 23 which may be internally screw threaded to take the pipe connection.

The fuel pressure chamber 19 of the unit is connected to the fuel inlet side of the carburetor by means of a pipe or conduit 24, such pipe connecting with a hollow boss 25 at the upper portion of the unit and on the companion member 16.

Both half sections or members 15, 16 are formed with outwardly projecting centrally disposed hollow projections 26 and 27 which are internally screw threaded and which communicate at their inner ends respectively with the chambers 18 and 19 and with opposite sides of the central portion of the diaphragm 17. Into one hollow projection 26 is removably threaded a headed plug 28 which may constitute also the attaching means by which the regulator unit is secured, for instance to the flange 29 on the intake manifold 30 of the internal combustion engine, as shown in Figure 1. An opening is made in this flange 29 to receive the shank of the plug 28, the portion of the flange 29 surrounding the opening being clamped between the head of the plug 28 and the outer end of the hollow projection 26; appropriate washers or gaskets being placed at opposite sides of the flange 29.

The hollow projection 27 on the other member 16 is adapted to threadedly and detachably receive the reduced externally threaded stud 31 of a cylindrical body 32 having preferably an external hexagonal form like that of the exterior of the plug 28 for the purposes of receiving a wrench or other tool by which these parts may be turned tightly into the threaded projections.

The body 32 contains cylinders 33 and 34 of differential diameters, the outer cylinder 33 being of greater diameter and connecting with the smaller diameter inner cylinder through a tapered section 35. A similar tapered section 36 is formed at the entrance mouth of the larger diameter cylinder 33.

Mounted to reciprocate in the cylindrical body 32 is a hollow piston comprising a large diameter section 37 and a smaller diameter section

38. These piston sections are respectively equipped with O-rings or other sealing devices 39 and 40. These rings tend to expand against the walls of the cylindrical sections 33 and 34 and to avoid leakage of the fuel pressure. They also constitute between them and about the reduced inner small diameter section 38 of the piston and the large diameter section 33 of the cylinder an annular chamber 41 for receiving fuel through a lateral connection 42 from a fuel induction pipe 43. As shown in Figure 1 this pipe connects with the conventional diaphragm type fuel pump 44.

A port 45 in the wall of the small diameter section 38 of the piston or plunger admits fuel from the chamber 41 into the internal space of the plunger by which such fuel passes to the fuel pressure chamber 19 through a valve or metering port 46 made in the inner end wall 47 of the plunger which provides a seat for a tapered pin or other type metering valve 48.

The valve is carried by and movable with the diaphragm 17 and its assembly is more particularly illustrated in Figure 9 in which the tapering section 48 is shown as located intermediate a narrow stem 49 extended off the narrowest section of the tapered portion 48 and an enlarged and slightly tapered section 50 extending off the greatest diameter of the intermediate tapered pin portion 48. The free end 51 is reversely tapered to facilitate introduction of the valve into and through the port 46 of the plunger.

The stem 49 carries a collar or shoulder 52 for receiving thereagainst a washer or gasket 53 which is adapted to slide over a threaded shank 54 of the valve and be received between the shoulder 52 and the adjacent side of the diaphragm 17. The threaded shank 54 extends through the diaphragm and receives thereover a lock washer 55 adapted to fit against the opposite side of the diaphragm 17 and to be held tightly thereagainst by a nut 56 threaded on the shank 54.

The outer end of the plunger 37, 38 is internally threaded to receive a threaded plug 57 having an outer slotted section 58 slidable in part-cylindrical grooves 59 in arms 60 and 61 which are carried as extensions of the cylindrical body 32.

An operating lever 62 is fulcrumed at 63 in the arm 60. Intermediate the arms 60 and 61 the lever is provided with a slot 64 for slidably receiving a pin 65 on the slotted outer section 58. The lever 62 plays through a slot 66 in the arm 60 and a slot 67 in the arm 61. A stop set screw 68 is adjustably threaded in the outer end of the arm 61 and projects into the slot 67 to engage an edge of the operating lever 62. The adjusted position of the set screw 68 is secured by a lock nut 69.

The companion arm 60 is provided with a curved finger 70 carrying a stop set screw 71 and a lock nut 72 for engaging an edge of the lever at the other side of the fulcrum 63.

The free end portion of the lever 62 carries a perforated barrel 73 rotatably or swivelly mounted thereon and having a set screw 74 secured in the perforation to anchor a Bowden wire 75. This wire extends as usual through a flexible casing and runs to a control knob 76 slidably mounted on the instrument panel 77 (Fig. 1).

In the use of the device, Figure 4 shows the dead cold position of the engine in which the flexible diaphragm 17 will seek an intermediate position in the casing holding the tapered pin

valve 48 in an initial position with respect to the metering plunger port 46. The control knob 76 will be in the "in" position against the instrument panel 77, having been pushed forwardly thereto by the operator incident to the previous normal running of the motor. The lever 62 is thus against the stop 68 and away from the stop 71. In this position the plunger is drawn to its outermost position as determined by the preselected adjusted position of the stop screw 68. This position of the parts is shown in Figure 4 in which the metering valve port 46 is in its outermost position enveloping a portion of the larger outer tapered section 50 of the metering valve. In this position the port area 46 is at a restricted value.

Now referring to Figure 5, in starting the motor, the control knob 76 is pulled out substantially at the same time that the starter switch is closed. The operating lever 62 is thereby rotated away from stop 68 and against stop 71 and incident to this rocking movement the plunger is pushed to its innermost position as preselected by the adjustment of the stop screw 71. The metering valve port 46 is thus advanced inwardly relatively to the metering valve with the port moving off the larger tapered valve section 50 and along the constantly diminishing tapered section 48. This action enlarges the port area at 46 thus permitting the engine suction to draw in a relatively great quantity of the fuel for starting purposes. A relatively enriched mixture is thus afforded for initial starting at low temperatures. This condition is shown in Figure 5 in which the diaphragm is still approximately straight and the metering valve 48 in its initial position due to the fact that as yet no substantial pressure has been built up in the exhaust manifold 21.

As the engine warms and its temperature increases the control knob 76 is gradually pushed forward to pull the plunger outwardly and cause the metering valve port 46 to seek a more enlarged portion of the tapering section of the valve pin 48. This action progressively reduces the port area 46 and thus restricts the volume of the fuel in proportion to the air in the induction system of the motor. In other words the ratio of the fuel to air mixture is then adjusted to running conditions. This port area adjustment may be preselected by the adjustment of the set screws 68 and 71 and by the size of the port area 46, and degree of the taper of the valve pin 48.

After the engine has attained operating temperature the plunger is pushed all the way in for normal operation and is not again disturbed throughout the running of the engine or until the engine is to be again restarted.

Through the use of this manual control medium it will thus be seen that the movement of this control knob, when used in connection with pressure type carburetors, allows this type of control to thus substitute in the place of the choking means found on the conventional carburetor, or also substitute as a fuel restricting device conventionally known as an altitude control.

Referring now to Figure 6, incident to running and after pressure has been built up in the exhaust manifold 21, such manifold pressure will be exerted on the diaphragm 17 and when this exhaust pressure exceeds the pressure of the fluid in the fuel pressure chamber 19 on the other side of the diaphragm 17 such diaphragm will be flexed in the direction of the plunger carrying

with it the metering pin valve 48 and moving such valve to a position where diminishing sections of the tapered portion of the valve are successively moved through the metering port 46 of the plunger; to the end that the fuel port area is progressively enlarged, admitting a progressively greater volume of fuel through the regulator and to the fuel jets of the carburetor whereby the proportion of fuel to air will be increased incident to increments in pressure in the exhaust manifold 21. These increments in pressure differ in response to increases in throttling, speed of, and loads on the engine.

This operation is illustrated in Figure 6 in which the diaphragm is flexed and the metering valve 48 moved inwardly relatively to the plunger.

This device thus acts as a secondary compensating medium to assist the carburetor jets in further conditioning the final air fuel ratio entering the induction system of the engine.

The indicated action of this regulator will be found especially true when used in connection with a pressure carburetor of the type disclosed in my co-pending application filed December 17, 1948, Serial No. 65,903.

In operation the fuel is entered into the regulator against a greatly reduced area, represented by the area of the metering pin 48 and the metering pin jet orifice 46, then allowed to flow externally across the face of the diaphragm before entering the carburetor. On the opposite side of the diaphragm the exhaust pressure will be working against the full area of the diaphragm and because of these two opposing pressure differentials the necessary compensating effect applied in terms of volume and pressure regulation is accomplished. For example assuming an exhaust manifold pressure of four pounds to obtain in the exhaust pressure chamber 18 and a fuel delivery output of four pounds pressure to be delivered to the fuel orifice 46, due to the differential areas of the diaphragm 17 and the orifice 46, a fuel pressure of less than four pounds will exist in the fuel pressure chamber 19, whereby the exhaust pressure in chamber 18 will force the diaphragm 17 to flex and the metering pin valve 48 to move inwardly with respect to the plunger thus opening the orifice 46.

This gives rise therefore to a change in fuel volume and in fuel pressure as concomitant characteristics and factors of the fuel output of the regulator delivery to the carburetor. The arrangement constitutes a nice regulation of both pressure and volume of fuel which neither exceeds nor falls short of the requirement of the pressure carburetor, and the fuel supply from the regulator is therefore not subject to the variability of the volume and pressure such as direct delivery of fuel from an A.-C. or conventional type diaphragm pump produces.

Installed between the carburetor and regulator is a pressure relief trim-valve or orifice 83 to which is connected a fuel return line 84, said line 84 entraining fuel to upper portion of fuel tank 85.

Assuming that the final carburetor jet is automatically sealed or closed on stopping the engine, a certain fuel pressure will remain trapped in the system and possibly escape into the manifold as wastage to evaporate or cause hard starting. This by-pass circuit automatically relieves fuel pressure and prevents waste.

The air-fuel ratio delivery for consumption within an internal combustion engine must be preselected or assembled accordingly to demands

imposed on the final jetting in the mixing chamber of the carburetor generally appearing in this order:

1. Atmospheric temperature.
2. Atmospheric pressure.
3. Type of fuel.
4. Timing.
5. Compression degree and form.
6. Humidity.
7. Cold engine starting.
8. Cold engine operation.
9. Hot engine starting.
10. Hot engine operation.
11. Full throttle acceleration against high resistance.
12. Full throttle acceleration against low resistance.
13. Part throttle cruising with medium engine revolutions.
14. Full throttle cruising with highest engine revolutions.

To supply a satisfactory air-fuel ratio to the engine, the carburetor final mixing assembly should be assisted by manual or automatic means to accomplish its objectives under various temperature, throttle, load, and speed conditions.

The exhaust discharge pressure against atmosphere or other cushioning and opposing systems is treated in terms of low, medium, and high values; averagely considered to be 0-1, 1-2½, 2½-4½ pounds respectively.

I have found that medium exhaust pressures are available during conditions 11 and 13, while high exhaust pressures are available during conditions 12 and 14.

By incorporating the use of exhaust pressures in the manner indicated throughout this invention these varying exhaust pressures are cooperatively forced to function some control over fuel pressure and volume according to throttle, load, and speed conditions imposed on the engine. Obviously, this supplements other controlling features.

Although I have disclosed herein the best form of the invention known to me at this time, I reserve the right to all such modifications and changes as may come within the scope of the following claims.

What I claim is:

1. A fuel-air ratio regulator for internal combustion engines having a carburetor, fuel pump, and exhaust manifold, comprising a movable member exposed to exhaust manifold pressure on one side and to the fuel on the opposite side, a fuel-metering orifice between the pump and carburetor, and a metering valve complementary to said orifice and connected to move with said member.

2. For use with an internal combustion engine having a carburetor, fuel pump and exhaust manifold, an improved fuel-air ratio regulator comprising a movable member, a casing divided by said member into exhaust pressure and fuel compartments, an inlet to the exhaust pressure compartment adapted to be connected to the exhaust manifold, an outlet from the fuel compartment adapted to be connected to the carburetor, an inlet to the fuel compartment adapted to be connected to the pump, a fuel orifice in the fuel compartment inlet, and a metering valve carried by said movable member and movable relatively to said orifice.

3. An improved fuel-air regulator as claimed in claim 2 characterized by the fact that the face

of the member subject to exhaust manifold pressure is greater than the port area of the fuel orifice.

4. An improved fuel-air regulator as claimed in claim 2 wherein the fuel orifice is adjustable relatively to the metering valve.

5. An improved fuel-air regulator according to claim 2 in which the fuel orifice is formed in a hollow plunger adjustably mounted in said fuel compartment inlet.

6. For use with an internal combustion engine having a carburetor, fuel pump and exhaust manifold, an improved fuel-air ratio regulator comprising a casing, a flexible diaphragm in said casing dividing the same into opposed exhaust pressure and fuel compartments, an inlet to the exhaust pressure compartment adapted to be connected to the exhaust manifold, an outlet from the fuel compartment, a conduit from the last mentioned outlet to the carburetor, an orifice in said conduit, a pipe connecting said orifice for recycling the fuel to the fuel tank or supply line to the pump, a fuel inlet to the fuel compartment of said casing, a restricted fuel orifice in said last mentioned inlet, and a valve carried by said diaphragm and movable relatively to the last mentioned fuel orifice.

7. For use with an internal combustion engine having a carburetor, fuel pump and exhaust manifold, an improved fuel-air ratio regulator comprising a casing, a movable member in the casing dividing the same into exhaust pressure and fuel compartments, an inlet to the exhaust pressure compartment adapted to be connected to the exhaust manifold, a fuel outlet from the fuel compartment adapted to be connected to the carburetor, a fuel inlet to said fuel compartment, a hollow plunger movably mounted in said fuel inlet accessible internally to the fuel supply and having a fuel metering orifice communicating with said fuel compartment, a valve carried by said movable member and movable through said orifice, and manual means for moving said plunger to adjust the position of the orifice to the valve.

8. A fuel-air ratio regulator as claimed in claim 7 characterized by the fact that said valve has a tapered section which when relatively moved to the orifice changes the port area.

9. A fuel-air ratio regulator according to claim 7 characterized by the fact that said manual means is a lever fulcrumed externally of said casing and connected to move said plunger, with adjustable stops for regulating the throw of the lever.

10. A fuel-air ratio regulator as claimed in claim 7 in which said manual means is a lever pivotally connected to said plunger, with a Bowden wire connected to said lever.

11. A fuel-air ratio regulator as claimed in claim 7 further comprising a cylinder for said plunger having extension arms thereon, adjustable stop screws in said arms, said manual means comprising a lever fulcrumed in one of said arms and pivotally connected to said plunger and disposed to engage said adjustable stop screws.

12. A fuel-air ratio regulator as claimed in claim 7 characterized by the fact that said plunger is of differential diameters, and a cylinder of differential diameters, adapted to receive respectively the two diametric portions of said plunger, said cylinder having a tapered wall between said different diameters, said piston having sealing rings adapted to engage said tapered

wall and to expand against the differential diametric portions of said cylinder.

13. A fuel-air ratio regulator as claimed in claim 7 characterized by the fact that said casing is made from identical sections having cored out portions to form said compartments and also having internally threaded extensions communicating respectively with said compartments, a plug removably mounted in the extension of the exhaust pressure compartment, and a cylinder for the plunger having a portion removably mounted in the fuel compartment extension.

14. A fuel-air ratio regulator as claimed in claim 13 characterized by the fact that said plug is headed and is adapted to act as a mounting screw in cooperation with a part of the engine.
